(57) CLAIM

The ornamental design for a bottle, as shown and described.

DESCRIPTION

FIG. 1 is a perspective view of the bottle;

FIG. 2 is a front view of the bottle;

FIG. 3 is a rear view of the bottle;

FIG. 4 is a right side view of the bottle;

FIG. 5 is a left side view of the bottle; and,

FIG. 6 is a top view of the bottle.

The bottom view, and portions of the bottle shown in broken lines, form no part of the claimed design.

1 Claim, 4 Drawing Sheets
